UNITED STATES PATENT OFFICE.

OBED C. BILLMAN, OF CLEVELAND, OHIO.

CAR-COUPING.

1,348,776.

Specification of Letters Patent.

Patented Aug. 3, 1920.

Application filed July 29, 1918. Serial No. 247,163.

To all whom it may concern:

Be it known that I, OBED C. BILLMAN, a citizen of the United States, residing at Cleveland, in the county of Cuyahoga and 5 State of Ohio, have invented certain new and useful Improvements in Car-Couplings, of which the following is a specification.

My invention relates to the construction of car couplers of the vertical plane or Master 10 Car Builders' type, the primary object of the invention being to provide a generally improved structure of this class which will not only be exceedingly simple in construction, but which will provide efficient means for 15 locking the knuckle in closed position, for locking the knuckle locking means in locked position to prevent accidental uncoupling, for maintaining the knuckle locking means in an unlocked position to permit a subsequent 20 uncoupling movement of the knuckle, and for causing the knuckle to be rotated to either an uncoupled or open position or to a coupled or closed position through the instrumentality of the knuckle locking means. 25 A further object is the provision of a coupler in which the stresses of buffing and draft shall be transmitted directly through the coupler-knuckle to the coupler-head, these parts being particularly designed and 30 adapted to provide great strength and durability in actual service.

My improvements are effected by changes in the form and construction of the coupler-head, the knuckle, the knuckle locking and 35 knuckle throwing members, and the relative arrangement and coöperation therebetween. There are other features of the invention residing in elemental combinations and particular construction of parts, all as will 40 hereinafter more fully appear.

With the above mentioned and other ends in view the invention consists in the novel construction, arrangement, and combination of parts, hereinafter described, illustrated 45 in some of its embodiments in the accompanying drawings, and particularly pointed out in the appended claims.

Referring to the drawings, forming a part of this specification, Figure 1, is a view, 50 partly in top plan and partly in horizontal section, of a car coupling constructed in accordance with this invention, the parts being shown in knuckle locking connected position.

Fig. 2, a horizontal sectional view of the 55 coupler, the parts being shown in knuckle-thrown position.

Fig. 3, a vertical longitudinal sectional view taken on line 3—3 of Fig. 1.

Fig. 4, a transverse or cross sectional view taken on line 4—4, of Fig. 1, the parts being 60 shown in locked position.

Fig. 5, a similar view, the parts being shown in lock-set position.

Fig. 6, a cross sectional view taken on line 6—6, of Fig. 2, the parts being shown in their 65 knuckle-thrown position, a slightly modified form of knuckle actuator actuating device or bell-crank, together with top connected lock actuating mechanism for operating the same, being shown.

Fig. 7, a detailed front elevation, partly in section, of the knuckle lock or pin with the modified form of knuckle actuator operating device or bell-crank, the parts being shown in their "lock-to-the-lock" position.

Fig. 8, an edge view of the locking pin, the knuckle actuator operating device or bell-crank being removed for purpose of clearer illustration of the parts.

Fig. 9, a detailed perspective view of the 80 locking pin, removed.

Fig. 10, a perspective view of the knuckle, removed.

Similar numerals of reference designate like parts throughout all the figures of the 85 drawings.

The improved coupler comprises a suitable coupler head 1, and a suitable shank or draw bar 1^a, said coupler head 1, preferably conforming to the contour lines prescribed by 90 the Master Car Builders' Association and, in the present instance, being provided with suitable horizontal strengthening ribs 1^b, on its guard arm side, as shown.

The knuckle 2, may be of any suitable and 95 convenient form and is provided with an arm 2^a, and is pivotally connected to the coupler head by means of a pivot pin 2^b.

As a means of preventing the knuckle 2, from being withdrawn from the coupler 100 head 1, in the event of the breakage of the pivot or knuckle pin 2^b, and particularly of relieving the latter of pulling and buffing strains and stresses in service, the knuckle arm 2^a, is provided with a laterally extending hooked portion 2^c, adapted to engage in a correspondingly formed recess 1^c, in the 105 coupler head.

Referring now to the improved knuckle actuating and locking mechanism to which 110 this invention particularly relates, it will be seen that I provide an improved knuckle

lock, in the present instance, in the specific form of a locking pin 3, vertically movable in suitable openings 1^a, in the upper and lower walls of the coupler head, said locking member or pin 3, comprising a head or block 3^a, affording a vertical shoulder 3^b, arranged to engage the tip or tail of the knuckle arm 2^a, when the latter is in closed position, as shown most clearly in Figs. 1 10 and 3, of the drawings.

The improved knuckle actuating mechanism, in the present instance, comprises a knuckle actuator in the form of a double or two-armed member 4, in the present instance, arranged to swing horizontally in the coupler head 1, and pivotally mounted therein, preferably by means of a pivot pin 4^c, said knuckle actuating member 4, being provided with an arm 4^a, movably connected 20 to the arm 2^a, of the knuckle, as hereinafter described, and extending at one side of the locking pin, and a second arm 4^b, extending at the opposite side of the knuckle locking member or pin 3, said arms 4^a and 4^b, in the 25 present instance, straddling the locking pin 3, and the arm 2^a, of the knuckle. The arm 4^b, preferably extends forwardly and is provided with beveled portions adapted to clear the tail or arm of the knuckle in the opening and closing movements of the latter and prevent any disarrangement of the parts.

The arm 4^a, extends at the rear of the knuckle arm 2^a, as a knuckle opening member, and as shown most clearly in Figs. 1, 35 and 2, of the drawings, the arm 4^a, extends into a recessed portion 2^a, terminating in a pocket 2^c, so that when the member 4^a, is operated by the mechanism hereinafter described, in the opening and closing movement 40 of the knuckle locking and releasing device the knuckle will be moved to its respective open and closed positions. If desired, the vertically movable knuckle lock or pin 3, may be supported in its elevated 45 position by means of a notch 3^c, in the side of its stem portion adapted to be engaged by the adjacent portion 4^d, of the arm 4^a, of the knuckle actuator member 4.

As a means of providing a "lock-to-the-lock" member, or in other words,—as a means for locking the lock or pin 3, in its closed position as against accidental release and until released by the lock actuating mechanism, (see Fig. 4) and particularly as 50 a means of affording a "lock-set" position when the lock is raised to an open position (see Fig. 5), as well as means of manually opening the knuckle through the lock operating mechanism (see Figs. 2 and 6), or, if desired, when the knuckle lock is raised to a slightly further elevated position (or in the form shown in Figs. 1 to 5, inclusive, of the drawings, of positively closing the knuckle with the closing movements of the lock, if 55 desired) the vertically movable knuckle lock

or pin is provided with a knuckle actuator operating member or movable arm 5, in the present instance in the form of what may be termed a "stem attachment" pivotally connected to the stem portion 3^d, of the locking 70 pin 3, by means of a pivot pin 6, said actuating arm or member 5, being preferably provided with a second arm 5^a, forming, in the present instance, conjointly with the arm 5, a bell-crank, said arm 5^a, extending in a 75 substantially horizontal direction for the purposes hereinafter referred to.

As a means of actuating the arm or member 5, for the purpose hereinafter mentioned, the arm 5^a, may be connected to a link lifter 80 in the form of a link 7, leading to the arm 8^a, of the rock or crank shaft 8, as shown in Figs. 1 to 5, inclusive, of the drawings,—and in which instance the arm or member 5, may be positively moved in opposite directions to 85 correspondingly move the knuckle actuating member 4, to correspondingly move the knuckle, or, if desired, the second arm 5^a, may extend in an opposite direction as the arm 5^d, into engagement with the lower wall 90 of the coupler head, as shown most clearly in Figs. 6 and 7, of the drawings, and in which instance the locking pin is elevated independently of the members 5, 5^a and 5^d, or in other words, the lock actuating mechanism 95 is not connected to the arm 5^d.

It will be seen that the arm or element 5, is arranged to operate in a recess 3^e, in the head or block 3^a, of the locking pin, and that the arm 5, extends between the arms of the 100 member 4, so as to alternately engage such arms in throwing the same in the act of opening and closing the knuckle, and as a specific means of locking the lock or pin 3, in its closed position the upper end of the 105 arm 5, is provided with a shoulder 5^b, adapted to initially engage the upper wall of the coupler head when the member 5, is in repose, as shown most clearly in Figs. 4 and 7, of the drawings, and it will be apparent 110 that upon the initial actuation of the arm 5^a, through the medium of the rock shaft 8, and arm 8^a, and the link 7, that said shoulder 5^b, will be initially moved out from under the 115 wall of the coupler to clear the latter, the head 5^c, coming into frictional engagement with the upper pin or lock opening of the coupler head, and the intermediate portion of the arm 5, coming into engagement with the inner or adjacent portion of the arm 4^b, 120 the arm 5, is thereby adapted to slidably pass upwardly therein and through the pin openings in the walls of the coupler head during the act of elevating the lock or pin 3.

It will be apparent that upon the elevation 125 of the pin or lock 3, to the position shown in Fig. 5, of the drawings, and the fulcrum portion 5^b, coming in contact with the lower wall of the coupler head that a further movement imparted to the second 130

arm 5^a, by the lock actuating lever mechanism will move the arm 5, to the position shown in Figs. 2 and 6, of the drawings, and will correspondingly move the arms of 5 the knuckle throwing or actuator member 4, thereby throwing the knuckle to its fully open position, and should it be desired to close the knuckle the latter may be closed by moving the lever arm 5^a, downwardly and 10 returning the arms 5 and 5^a, to their original position, it being obvious in such movement that the intermediate portion of the member 5, will engage the arm 4^a, returning the same to its original position, the engagement 15 of the extreme or rounded end of such arm within the notched pocket 2^c, causing the knuckle to return to the closed position shown in Figs. 1, 3 and 4, of the drawings.

When the arm 5, is moved to its extreme 20 knuckle opening position, it will be seen that the recess 5^e, will receive the edge of the upper wall of the coupler head, as shown in Fig. 6, and when tension is released on the second arm 5^a, by the relaxation of the 25 knuckle operating mechanism the lock or pin 3, and the arm or member 5, will be permitted to relax and be free to assume their original positions, so that when the knuckle reaches its closed position the pin will automatically drop in position.

In the modified form shown in Figs. 6 and 7, of the drawings, the knuckle actuator operating member 5, and crank arm 5^a, are actuated through the direct actuation of the 35 lock or pin 3, from the top of the latter, such actuating member 5, being actuated by means of the curved arm 5^a, coming in contact with the bottom of the coupler head, and hence as a means of initially moving the shoulder 5^b, 40 out of its "lock-to-the-lock" position, a vertically movable lock lifter member or detent 9, is mounted in an opening 3^f, in the lock or pin 3, said lock lifter having a projection 9^a, engaging in a recess having an inclined 45 shoulder 5^e, of the member 5, just below the lock-set shoulder 5^b, said lock lifter member being initially elevated through the medium of a clevis 10, having a cross pin 11, operating in an elongated slot 3^g, in the top of the 50 pin or lock 3, the first or initial movement of such clevis 10, and lifter 9, causing the projection 9^a, to move the arm 5, laterally sufficiently to enable the shoulder 5^b, to clear the upper wall of the coupler head, it being 55 obvious that upon the further movements of the lock or pin 3, either a lock-set position may be given to the locking pin, as herein-after described, or if desired the knuckle may be given its fully open position through 60 the medium of the arm 5^a, and the lateral movement of the member 5, in engagement with the arm 4^b of the knuckle actuating member, as hereinbefore described, but in this form it will be apparent that no means

are provided for manually closing the 65 knuckle.

Referring now to the "lock-set" feature of this invention it will be seen that a lock-set shoulder 3^h, is provided at the lower side of the member 5, and the lower end of the arm 70 or member 5, is provided with a slightly inclined slot 12, adapted to swing on the pivot pin 6.

In the form of the invention, shown in Figs. 1 to 5, inclusive, when the locking pin 75 is moved from the position shown in Fig. 4, to a position slightly above that shown in Fig. 5, (the knuckle releasing position of the locking pin) the tension on the link 7, will cause the lower arm 5^a, (or the arm 5^a, by 80 the upward movement of the pin in the form shown in Figs. 6 and 7) to be moved laterally to the position shown in Fig. 5, (the slot 12 permitting of the movement) and thus carry the lock-set shoulder 3^h, in engagement 85 with the lower wall of the coupler head, as indicated in Fig. 5.

As the knuckle is moved to its open position, either manually through the locking pin or automatically when two connected 90 couplers separate, the two-armed member 4, will swing on the pivot pin 4^c and the arm 4^a, of the two-armed actuating member 4, coming in contact with the adjacent inner side of the arm 5, will carry the lock-set 95 shoulder 3^h, off of the lower wall of the coupler head, so that the knuckle locking pin will be supported on the rear side of the two-armed member 4, by the pin supporting shoulder 3^c, hereinbefore referred to, (or 100 if desired the head or block 3^a, of the pin may be supported on the hooked portion 2^c, of the locking pin, as is common practice in couplers of this type) and it will thus be observed that when the knuckle is moved 105 to its closed position the locking pin will automatically engage the tail of the knuckle, as hereinbefore referred to.

It will also be observed that when the knuckle is moved to its open position and 110 the parts are in lock-set position, as shown in Fig. 5, the swinging of the knuckle and the two-armed member 4, will move the arm 5, to its extreme knuckle opening position and thereby carry the lock-set shoulder 3^h, 115 to such a position as to enable the lock-set shoulder 3^h, to clear the lower wall of the coupler head, as shown in Fig. 6, so that automatic coupling will take place when the knuckle is moved to its closed position. 120

From the foregoing description, taken in connection with the accompanying drawings, the operation and advantages of my invention will be readily understood.

Having thus described some of the em- 125 bodiments of my invention, what I claim and desire to secure by Letters Patent, is,—

1. In a car coupling, a coupler head, a

- knuckle, a lock, a knuckle actuator, and bell-crank lock-to-the-lock means for moving the latter with the movements of said lock.
2. In a car coupling, a coupler head, a knuckle, a lock, a knuckle actuator, and lock-set lever means movable on said lock for moving the actuator with the movements of said lock.
3. In a car coupling, a coupler head, a knuckle, a lock, a horizontally swinging knuckle actuator, and a lock-to-the-lock and lock-set lever for actuating the latter with the movements of said lock.
4. In a car coupling, a coupler head, a knuckle, a knuckle lock, a lock lifter, a two-armed actuating member, and a bell-crank member for actuating the latter with the movements of said lock lifter and lock, said bell-crank member being engaged and moved by said lock-lifter relative to said lock prior to the movement of the latter.
5. In a car coupling, a coupler head, a knuckle, a lock, a knuckle actuator, and a lock-to-the-lock and lock-set bell-crank for actuating the latter with the movements of said lock.
6. In a car coupling, a coupler head, a knuckle, a knuckle lock, a knuckle actuating member, and a lock-to-the-lock bell-crank member for actuating the latter through the movements of said lock.
7. In a car coupling, a coupler head, a knuckle, a knuckle lock, a knuckle actuator, and a relatively movable lock-to-the-lock and actuator actuating pivoted lever member carried by and movable with the movements of said lock.
8. In a car coupling, a coupler head, a knuckle, a knuckle lock, a horizontally swinging knuckle actuating member, and a pivoted lever member movable on and with said lock for actuating said knuckle actuating member.
9. In a car coupling, a coupler head, a knuckle, a knuckle lock, a lock lifter, a horizontal actuating member, and a vertical bell-crank member movable with said lock lifter and relatively to said lock for actuating said knuckle actuating member.
10. In a car coupling, a coupler head, a knuckle, a knuckle lock, a horizontal knuckle actuator, bell-crank, and a relatively movable lock-to-the-lock and actuator operating bell-crank movable with the movements of said lock.
11. In a car coupling, a coupler head, a knuckle, a knuckle lock, a horizontal two-armed knuckle actuator, and vertical lever means adapted to lock said lock in locked position and to release said lock and actuate said knuckle actuator when said lock is moved to and above its knuckle releasing position.
12. In a car coupling, a coupler head, a knuckle, a knuckle lock, a horizontally swinging two-armed knuckle actuator straddling said lock, and lock actuating lever means to lock said lock in locked position and to release said lock and actuate said knuckle actuator when said lock is moved to and above its lock-set positions, respectively.
13. In a car coupling, the combination with the coupler head, a pivoted knuckle, and a lock therefor; of a knuckle actuating member, and a pivoted lock attachment actuating said knuckle actuating member with the opening and closing movements of said lock attachment.
14. In a car coupling, the combination with the coupler head; of a pivoted knuckle, a vertically movable lock therefor, a knuckle actuating bell-crank member, and a bell-crank lock attachment pivoted on the said lock for actuating said knuckle actuating member and knuckle with the opening movement of said lock attachment.
15. In a car coupling, the combination of a coupler head, a knuckle, a knuckle lock, a pivotally mounted two-armed knuckle actuator connected to and movable simultaneously with the knuckle on the opening and closing movements thereof, and lever means operatively connected to said knuckle actuator and movable with the opening and closing movements of said lock, said means comprising a lock-to-the-lock member adapted to initially unlock said lock and upon further movement to actuate said knuckle actuator.
16. In a car coupling, a coupler head, a knuckle, a knuckle lock, a knuckle actuator, and a lock-to-the-lock and lock-set lever member movable on and relatively to said lock and operatively connected to said actuator and operating said actuator through the movements of said lever member after the latter is moved to its lock-set position.
17. In a car coupling, a coupler head, a knuckle, a knuckle lock, a knuckle actuator, and a lock-to-the-lock bell-crank movable on and relatively to said lock operatively connected to said actuator and operating said lock and actuator through the movements of said bell-crank when the latter is moved above its lock-set position.
18. In a car coupling, the combination with a vertically movable knuckle lock, and a substantially U-shaped horizontally swinging knuckle actuator straddling the knuckle lock; of a vertically swinging bell-crank pivoted on and movable vertically with said lock and having one arm in operative engagement with said knuckle actuator and normally forming a lock-to-the-lock and the other arranged to be actuated with the elevation of said lock.
19. In a car coupling, a coupler head, a

- knuckle, a knuckle lock, lock actuating mechanism, a two-armed knuckle actuator, and a two-armed member movable relatively to said lock having one arm in engagement with said knuckle actuator and normally locking said lock in locked position, and the other extending outside of said coupler head for initially releasing said lock and simultaneously actuating the parts 10 with the opening movement of said lock actuating mechanism.
20. In a car coupling, a coupler head, a knuckle, a knuckle lock, a horizontal two-armed knuckle actuator straddling said lock, lock actuating mechanism, and a two-armed member pivoted on and movable with said lock having one arm in engagement with said knuckle actuator forming a lock-to-the-lock and the other extending outside of 15 said coupler head for initially releasing said lock-to-the-lock and then simultaneously actuating the knuckle actuator with the opening movement of said lock actuating mechanism.
25. 21. In a car coupling, the combination with a coupler head, a vertically movable knuckle locking pin having relatively movable pin lift mechanism, and a substantially U-shaped horizontally swinging knuckle actuator straddling the knuckle locking pin; of a vertically swinging bell-crank pivoted at one side of said lock and having one arm in operative engagement with said knuckle actuator and normally forming a lock-to- 30 35 the lock and adapted to be released by said pin lift mechanism and the other arm arranged to be actuated with the elevation of said lock to move said bell-crank and knuckle actuator in co-operative relation to each other.
22. In a car coupling, the combination of a coupler head, a knuckle, a knuckle lock, a pivotally mounted two-armed knuckle actuator, and independent means operatively connected to said knuckle actuator and relatively movable on and with the movements of said lock, said means comprising a lock-set portion adapted to slidably engage said coupler head when the lock is raised and 40 a lock-to-the-lock member adapted to initially unlock said lock arm upon further movement to actuate said knuckle actuator and move said lock-set portion out of engagement with said coupler head.
55. 23. In a car coupling, a coupler head, a knuckle, a knuckle locking pin having a stem provided with a pin supporting shoulder, a two-armed stem attachment on said locking pin, and a two-armed horizontally 50 movable knuckle actuating member straddling the locking pin, one of said arms being in engagement with and adapted to swing with the knuckle and to engage said pin supporting shoulder when the knuckle is open, and the other being arranged to be engaged by the stem attachment when the latter is moved by the locking member whereby the knuckle is moved to its open position.
24. In a car coupling, a coupler head, a knuckle, a knuckle locking pin having a notched portion in its side, a two-armed pin attachment pivoted on said locking pin and forming a lock-to-the-lock and lock-set member, and a two-armed horizontal knuckle actuating member, one of said arms being in engagement with and adapted to swing the knuckle, and the other being arranged to be engaged by the pin attachment when the latter is moved to lock releasing position whereby the knuckle is moved to its open position.
25. In a car coupling, a coupler head, a knuckle, a knuckle lock, a two-armed knuckle actuator straddling the knuckle lock, and a bell-crank knuckle actuator operating member pivoted on said lock and having one arm arranged between the arms of said two-armed knuckle actuator and the other arm arranged outside of said coupler head to be engaged and actuated to impart movement to said parts with the opening and closing movements of said knuckle lock.
26. In a car coupling, the combination with a knuckle, a knuckle lock, and a knuckle actuator; of a two-armed knuckle actuator operating device pivotally mounted and adapted to be actuated simultaneously with the lock and to open and close said knuckle with the opening and closing movements of said lock, one of said arms forming a lock-to-the-lock and the other forming an operating lever for initially releasing said lock-to-the-lock and for operating said knuckle actuator after said lock-to-the-lock is moved to its unlocked position.
27. In a car coupling, the combination with a vertically movable knuckle lock, and a horizontally swinging two-armed knuckle actuator straddling the knuckle lock; of a two-armed knuckle actuator operating member pivoted at one side of said lock, one of said arms being arranged at the side of the locking pin and between the arms of said knuckle actuator to operate the latter and the other being arranged to be operated by the lock actuating mechanism as said lock is operated.
28. In a car coupling, the combination with a knuckle, a knuckle lock, and a U-shaped knuckle actuator; of a two-armed knuckle actuator operating device pivotally mounted and adapted to be actuated with the lock and to open and close said knuckle with the opening and closing movements of said lock, one of said arms extending along said lock and between the arms of said U-shaped knuckle actuator forming a lock-to-the-lock and the other forming an

- operating lever for initially releasing said lock - to - the - lock and for operating said knuckle actuator after said knuckle lock is moved to its unlocked position.
29. In a car coupling, a coupler head, a knuckle, a vertically movable gravity operated knuckle lock, a two-armed horizontally movable knuckle actuator straddling the knuckle lock, and a transversely movable bell-crank knuckle actuator operating member pivoted at one side of said lock and having one arm arranged between the arms of said two-armed knuckle actuator and normally forming a lock-to-the-lock and the other arm arranged outside of and below said coupler head to be engaged and actuated to impart movement to said parts with the opening and closing movements of said knuckle lock.
30. In a car coupling, the combination with a coupler head; of a knuckle pivotally mounted therein, a knuckle lock, a knuckle actuator member, a knuckle actuator operating device carried by and operable with said lock, said device including a lock-to-the-lock normally engaging said coupler head to lock said lock in locked position and being adapted to actuate said knuckle actuator when said lock is moved to its open position and is released by said lock-to-the-lock device, said knuckle actuator operating device being provided with a lock-set portion adapted to engage said coupler head when said lock is moved to its open position and to be disengaged therefrom when said knuckle actuator is operated by said actuator operating device.
31. A car coupling, comprising a coupler head, a knuckle lock vertically movable therein, a two-armed knuckle actuator straddling said knuckle lock and pivoted in said coupler head to swing horizontally therein, a bell-crank member pivoted at one side of said lock and operatively connected to said knuckle actuator and normally locking said lock in locked position, a lock lifter member movable on said knuckle lock and operatively connected to said arm of said bell-crank to initially release the latter from its lock-to-the-lock position, the other arm of said bell-crank coming into engagement with a fixed portion of said head with the further elevation of said lock by said lock lifter.
32. In a car coupling, a coupler head, a knuckle, a lock, a lock lifter vertically movable relative to said lock, a knuckle actuator, and a bell-crank movable initially by said lock lifter and operating said knuckle actuator when said lock is moved beyond its unlocked position.
33. In a car coupling, a coupler head, a knuckle lock vertically movable therein, a two-armed knuckle actuator straddling said knuckle lock and pivoted in said coupler head to swing horizontally therein, a bell-crank member pivoted at one side of said lock and having one arm operatively connected to said lock lifter and normally locking said lock in locked position, a lock lifter member movable on said knuckle lock and operatively connected to said arm of said bell-crank to initially release the latter from its lock-to-the-lock position, the other arm of said bell-crank coming into engagement with a fixed portion of said head with the further elevation of said lock by said lock lifter.
34. In a car coupling, a coupler head, a knuckle, a lock, a lock lifter vertically movable relative to said lock, a knuckle actuator, and a bell-crank movable initially by said lock lifter and operating said knuckle actuator when said lock is moved beyond its unlocked position.
35. In a car coupling, a coupler head, a knuckle, a lock, a lock lifter, a two-armed knuckle actuator, and a two-armed pivoted member operatively connected to said lock lifter and knuckle actuator and actuating the latter when said lock is moved above its knuckle releasing position.
36. In a car coupling, a knuckle lock, a knuckle actuator, a lock lifter and a two-armed lock-to-the-lock member pivoted on said lock and having one arm in engagement with said actuator and the other arm arranged to be actuated with the knuckle opening movement of said lock.
37. In a car coupling, a bodily movable knuckle lock, a two-armed knuckle actuator, and a two-armed lock-to-the-lock device pivoted on and movable with said lock and engaging and actuating said knuckle actuator with the movement of said lock beyond its knuckle releasing position.
38. In a car coupling, a knuckle actuator, a pivoted two-armed knuckle actuator operating device, one of the arms forming a knuckle actuator moving member initially movable relative to said knuckle actuator and the other an operating lever for initially moving said arm relative to said knuckle actuator and then moving all of the parts simultaneously with the movement of

the lock through the lock actuating mechanism.

39. In a car coupling, the combination with a vertically movable knuckle lock, a 5 relatively movable lock lifter and a two-armed horizontally swinging knuckle actuator; of a vertical lock-to-the-lock lever pivoted on and movable vertically with said lock and arranged to be moved to first unlock 10 lock said lock and to engage and operate said actuator when said lock is moved beyond its unlocked position.

40. In a car coupling, the combination with a vertically movable knuckle lock, and 15 a two-armed horizontally swinging knuckle actuator; of a vertical lock-set lever pivoted on and movable vertically with said lock and arranged to engage and operate said actuator when said lock is moved beyond its 20 unlocked position.

41. In a car coupling, the combination with a vertically movable knuckle lock, and a two-armed horizontally swinging pivoted knuckle actuator; of a vertical lock-to-the-lock lever pivoted on and movable vertically with said lock and arranged to engage and operate said actuator when said lock is moved beyond its unlocked position.

42. In a car coupling, a knuckle lock, a 30 horizontally movable two-armed knuckle actuator, and a two-armed vertical lever member on and movable with said lock, one of the arms being in operative engagement with said actuator and normally forming a lock-to-the-lock and the other forming an operating lever to be operated through the lock actuating mechanism as said lock is moved.

43. In a car coupling, a knuckle arm having a pocket extending toward its pivoted 40 portion, and a horizontally swinging two armed knuckle actuator having an arm longitudinally movable in said pocket and opening and closing said knuckle arm with the opening and closing movements imparted to said knuckle arm through the other arm of said actuator.

44. In a car coupling, a knuckle arm having a recess in its rear portion terminating in a pocket near and extending toward its 50 pivoted portion, and a pivoted two armed knuckle actuator having an arm swinging in said recess and terminating in a head portion longitudinally movable in said pocket and opening and closing said knuckle arm with the opening and closing movements of said knuckle arm through the other arm of said actuator.

45. In a car coupling, a knuckle, a lock therefor, a knuckle actuator, and a two-armed actuator operating device actuated simultaneously with the lock to open said knuckle, one of the arms forming a lock-set and actuator moving member and the other an operating lever for initially operating

said lock-set and then operating said actuator moving member.

46. In a car coupling, the combination with the coupler head; of a pivoted knuckle, a vertically movable lock therefor, a knuckle actuating bell-crank, and a bell-crank lock 70 attachment for actuating said knuckle actuating bell-crank and knuckle with the opening movements of said lock.

47. A locking device for car couplers, comprising a knuckle lock, a relatively movable lock lifter, and a pivoted lock-to-the-lock knuckle actuator moving lever member carried by and movable relatively to said knuckle lock and operatively connected to said lock lifter to initially move and release 80 said lock-to-the-lock knuckle actuator moving lever member independently of and prior to the initial movement of said knuckle lock.

48. A knuckle locking and actuating 85 mechanism for car couplers, comprising a knuckle-lock, a two-armed knuckle actuator straddling the knuckle-lock, one of the arms being operatively connected to and adapted to swing the knuckle to its open and closed 90 positions, a knuckle actuator moving lock-to-the-lock lever member on said lock, and a movable lock-lift member connected to and adapted to initially release said lock-to-the-lock lever member.

49. A knuckle locking and actuating mechanism for car couplers, comprising a knuckle-lock, a two-armed horizontally swinging knuckle actuator, one of the arms connecting and swinging the knuckle to its 100 open and closed positions with like movements of said knuckle actuator, a knuckle actuator moving lock-to-the-lock lever member movable relative to said lock and arranged to engage said knuckle actuator, and 105 a lock-lift member movable relative to said lock adapted to initially release said lock-to-the-lock lever member.

50. A lock for car couplers, comprising a lock having a vertically movable lock lifter, 110 and a bell-crank member having one arm forming a lock-to-the-lock initially movable relatively to said lock and the other positively actuating said bell-crank when initially released, one of said arms being engaged and released by said lock lifter when the latter is relatively moved vertically prior to the initial elevation of said lock.

51. A knuckle lock for car couplers, comprising a knuckle arm engaging block terminating in a depending stem portion, a lock-to-the-lock bell-crank pivotally mounted on and vertically movable with said stem portion, and a lock lift member initially movable relative to said block and initially 120 engaging and releasing said bell-crank prior to the elevation of said block.

52. A locking device for car couplers,

comprising a knuckle lock, a lock lifter, initially movable relative to said lock and a lock-to-the-lock and lock-set lever member movable relatively to said knuckle lock and lock lifter when in locked position and moved by the latter to unlocked and lock-set positions prior to the elevation of said lock beyond its knuckle releasing position when

the knuckle is in its closed position in mating engagement with an opposed coupler.

10

In testimony whereof I have affixed my signature in the presence of two witnesses.

OBED C. BILLMAN.
